Primary Examiner — Joseph Kukella*Assistant Examiner* — Darrul J Dardenne(74) *Attorney, Agent, or Firm* — The Dobrusin Law Firm P.C.(57) **CLAIM**

An ornamental design for a portion capsule, as shown and described.

DESCRIPTION

FIG. 1 is a front view of a portion capsule showing my new design, the back view being a mirror image of this view; FIG. 2 is a right side view of the portion capsule, the left side view being a mirror image of this view; and,

FIG. 3 is a top view of the portion capsule.

In the drawings, the broken lines depict portions of the article that form no part of the claimed design.
